CLAIM

We claim the ornamental design for a handle for spoon or fork, as shown and described.

DESCRIPTION

FIG. 1 is a perspective view of a handle for spoon or fork according to the present disclosure;

FIG. 2 is a front view of a handle for spoon or fork according to the present disclosure;

FIG. 3 is a rear view of a handle for spoon or fork according to the present disclosure;

FIG. 4 is a left side view of a handle for spoon or fork according to the present disclosure;

FIG. 5 is a right side view of a handle for spoon or fork according to the present disclosure;

FIG. 6 is a top view of a handle for spoon or fork according to the present disclosure;

FIG. 7 is a bottom view of a handle for spoon or fork according to the present disclosure;

FIG. 8 is a first reference view of a handle for spoon or fork with a spoon and a fork according to the present disclosure; and,

FIG. 9 is a second reference view of a handle for spoon or fork with a spoon and a fork according to the present disclosure.

The broken lines in the figure drawings showing portions of the article, the spoon head, the fork head, and exemplary second handle form no part of the claimed design.

1 Claim, 9 Drawing Sheets
